OUTBOARD MOTOR IMPELLER HUB

George E. Carlson, Minneapolis, Minn., assignor to Minnesota Rubber Company, Minneapolis, Minn., a corporation of Minnesota

Filed Feb. 23, 1961, Ser. No. 64,031

Term of patent 14 years

(Cl. D71—1)

FIG. 1.

FIG. 2.

FIG. 3.

FIG. 1 is an end elevational view of an outboard motor impeller hub showing my new design;

FIG. 2 is a side elevational view thereof; and

FIG. 3 is a cross-sectional view taken substantially along line 3—3 of FIG. 1 looking downwardly in the direction of the arrows.

I claim:

The ornamental design for an outboard motor impeller hub, as shown.
